(57) **CLAIM**

The ornamental design for a pet feeder, as shown and described.

DESCRIPTION

FIG. 1 is a front view of a pet feeder showing our new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof;

FIG. 8 is a perspective view thereof showing the unfolded state without the bowls; and,

FIG. 9 is a perspective view thereof showing the folded state without the bowls.

The broken lines showing the bowls illustrate environmental structure that form no part of the claimed design.

All other broken lines illustrate portions of the pet feeder that form no part of the claimed design.

1 Claim, 9 Drawing Sheets
